UNITED STATES PATENT OFFICE

104,689

DESIGN FOR A TEXTILE FABRIC OR SIMILAR ARTICLE

Adolph C. Jaeger, Port Chester, N. Y.

Application January 8, 1937, Serial No. 66,949

Term of patent 7 years

To all whom it may concern:

Be it known that I, Adolph C. Jaeger, a citizen of the United States, residing at Port Chester, county of Westchester, State of New York, have invented a new, original, and ornamental Design for a Textile Fabric or Similar Article, of which the following is a specification, reference being had to the accompanying drawing which forms a part thereof, in which the figure shows in plan view a textile fabric embodying the design.

This is an all-over design, in which figures offering substantially the same appearance are repeated in sequence with varying position relationship as shown.

I claim:

The ornamental design for a textile fabric or similar article substantially as shown and described.

ADOLPH C. JAEGER.
